HUMFREY ANDREWES, OF LONDON, ENGLAND, ASSIGNOR OF ONE-HALF TO RADIO PATENTS CORPORATION, OF NEW YORK, N. Y.

ELECTRIC PICK-UP DEVICE

Application filed July 28, 1928, Serial No. 296,059, and in Great Britain February 24, 1928.

This invention broadly refers to an arrangement for translating mechanical movements into corresponding electrical variations and is more particularly directed to means for transforming the vibrations of the stylus of a phonograph into electrical variations for reproduction by a loudspeaker. Such devices have become known under the name of phonograph pick-up devices and 10 are so constructed that they can be attached to an ordinary phonograph, in an easy manner. They present important advantages as compared to the direct reproduction by the stylus acting on the phonograph diaphragm, 15 which primarily consists of a higher quality of the tones reproduced.

One object of this invention is to receive equal reproduction of the notes of the entire musical scale to be reproduced.

Another object of this invention is to provide combined electro-static and electro-magnetic pick-up means in such a way as to secure equal quality of reproduction of the entire band of frequencies to be translated.

The invention is more fully and specifically described by the following detailed disclosure taken in reference to the accompanying drawings of which

Fig. 1 is a sectional elevation of the pick-up device constructed in accordance with my invention.

Fig. 2 is a front elevation of the device with the sound box cover, stylus, stylus lever, and part of the diaphragm removed.

Fig. 3 is a diagram of connections.

In gramophone pick-up and amplifying devices using the electro-magnetic principle, it has been found that the relationship between the response and frequency is not linear and usually there is a considerable falling off in the response of the pick-up at the lower frequencies, whereas in those using the electrostatic principle there is a considerable falling off at the higher frequencies.

The invention consists of the arrangement of an electro-magnet, preferably annular in shape, having an annular rim as one pole and a centre boss as the other pole, between which poles is disposed a thin annular winding, and a stretched steel diaphragm mounted in close

proximity to the pole pieces, whereby the centre pole piece and the diaphragm constitute the two electrodes of an electrostatic device, similar to that as described and claimed in my U. S. application Serial No. 268,006, 55 filed April 6, 1928. In this combined arrangement the principles of the electro-magnetic and the electrostatic devices may be used simultaneously.

Referring first to Fig. 3, in the present circuit arrangements the electrostatic portion of the pick-up connected in the usual manner wherein the centre boss 1 of the electro-magnet 6 constitutes the back electrode and is connected to the positive pole of the polarizing battery 2 which is preferably variable and which is at the same time the anode battery for the amplifying three-electrode tubes V_1 and V_2 arranged in resistance coupling connection. The magnetic diaphragm 3 is connected to the grid of an amplifying valve V_1 , and a coupling resistance 23' is connected between the said grid and the grid bias lead 11. The winding 5 on the electro-magnet 6 is connected through a battery 7 to the primary 8 of a step-up transformer 9 and the secondary 10 of the transformer is connected through the variable condenser 18 to the grid 4 at the minus grid bias lead 11 of the tube V_1 . A choke 12 is preferably connected in the lead 13 between the diaphragm 3 and the grid of the valve V_1 , and a resistance 14 is included in the circuit of the anode of the said valve, forming together with a further lead resistance 15 and a condenser 21 the 85 normal resistance coupling element between the tubes V_1 and V_2 . 22 is a heating battery for the tubes and 23 is a grid biasing battery. 24 represents a loudspeaker inserted in the anode circuit of the last tube for reproduction 90 of the sound vibrations of diaphragm 3. 19 is a by-pass condenser bridging the part of resistance 20 inserted in the electrostatic pick-up circuit.

The action of the circuit is as follows:— 95 Movements of the needle 16 actuated by variation of the grooves in the gramophone record cause the stylus 17 to actuate the diaphragm 3 thereby varying the distance between the diaphragm and the boss 1 which constitutes 100

the back electrode and the centre pole piece. This movement has two effects: Firstly it causes a variation in capacity between the two electrodes represented by the pole-piece 5 and the diaphragm, thereby producing an alternating E. M. F. across the resistance 23' connected between the grid and negative grid bias lead of the first amplifying tube V_1 ; secondly the movement causes the flux in the 10 electro-magnet 6, formed in the winding 5 and the pole piece 1 producing an alternating E. M. F. across the primary 8 of the transformer 9 which is transferred to the grid of the tube V_1 through the variable condenser 15 18. The object of the introduction of the choke 12 in the lead of the grid of tube V_1 to the diaphragm 3 is to prevent the shunting of the higher frequencies which are produced by the electro-magnetic system, and in a similar 20 manner the object of the introduction of the variable condenser 18 into the lead of the grid of tube V_1 and the transformer 9 is to prevent the shunting of the lower frequencies by the electrostatic system by the step-up transformer 25 9 of the electro-magnetic system. The proportion of the E. M. F. produced on the grid of amplifying tube V_1 from each of the two systems may be varied by means of the polarizing potential tapped from the potentiometer 20 in the case of the electrostatic system and by the variable resistance 21 in the primary circuit of the electro-magnetic system. The actual values of the capacities of the variable condenser 18 and the choke 12 30 35 depend on the constants of the pick-up device itself.

Referring to the structural embodiment of the pick-up device shown by Figures 1 and 2, similar numerals refer to similar elements. 4 40 is the metallic tubular extension for connection with a horn or the like when using the device as an ordinary gramophone, which is connected to a terminal 24 serving for connection to ground. 25 and 26 are terminals serving for connection to the iron core 6 and the diaphragm 3, respectively, and 27 and 28 are binding posts serving for connection with the terminals of the magnet coil 5.

What I claim to be secured by Letters Patent of the United States is:

1. An arrangement for translating mechanical movements into corresponding electrical variations comprising a flexible diaphragm subject to said movements, an electric circuit producing a magnetic field associated with said diaphragm, a further electric circuit including a capacity element, an electrode of said capacity element including said diaphragm, and means for combining the electric variations occurring in said electric circuits due to the movement of diaphragms in a common translating device.

2. An arrangement for translating the movements of the stylus of a phonograph into electrical variations, comprising a flexible

diaphragm, means connecting said diaphragm to said stylus for imparting to it said movements, an electric circuit linked with a magnetic field associated with said diaphragm, a further electric circuit including 70 a capacity element of which said diaphragm is a part, and means for combining the electric variations occurring in said electric circuits due to the movement of said diaphragm to a common translating device. 75

3. An arrangement for translating the movements of the stylus of a phonograph into electrical variations, comprising a flexible diaphragm, means connecting said diaphragm to said stylus for imparting to it said 80 movements, an electric circuit linked with a magnetic field associated with said diaphragm, a further electric circuit including a capacity element of which said diaphragm is a part, an electric discharge device having main electrodes and a control electrode, means to simultaneously apply varying potential to said control electrode in accordance with electric variations in said electric circuits, and an electric reproducing device actuated by the 85 output circuit of said discharge device.

4. An arrangement for translating the movements of the stylus of a phonograph into electrical variations, comprising a flexible diaphragm of magnetic material subject to 90 said movements, pole pieces arranged opposite said diaphragm, an electric circuit including a winding arranged on said pole pieces, a further electric circuit including a capacity element constituted by said diaphragm and 95 said pole pieces and means for combining electric variations in said electric circuits in a common translating device.

5. An arrangement for translating the movements of the stylus of a phonograph into electrical variations, comprising a flexible diaphragm of magnetic material subject to 100 said movements, pole pieces arranged opposite said diaphragm, an electric circuit including a winding arranged on said pole pieces, a further electric circuit including a capacity element constituted by said diaphragm and 105 said pole pieces, an electric discharge device having main electrodes and a control electrode, means to simultaneously apply varying potential to said control electrode in accordance with electric variations in said electric circuits, and an electric reproducing device actuated by the output circuit of said 110 discharge device.

6. An arrangement as in claim 5, means for providing a variable polarizing voltage for the electro-static element and an exciting polarizing current for the magnetic element of 115 said translating arrangement.

7. An arrangement as in claim 5, in which electrical blocking means are provided in one circuit for the single resulting current for 120 preventing variations of certain frequencies 125

translated by one of the elements from being short-circuited by the other element.

8. An arrangement for translating mechanical movements into corresponding electrical variations comprising a flexible diaphragm subject to said movements, an electric circuit producing a magnetic field associated with said diaphragm, a further electric circuit including a capacity element, an electrode of said capacity element including said diaphragm, means for combining the electric variations occurring in said electric circuits due to the movement of diaphragms in a common translating device and means for varying the components of the single electric currents produced by said variations of said electric and magnetic field.

9. In an arrangement for translating the mechanical movements of a stylus into corresponding electrical variations, comprising a moving member adapted for influencing an electrostatic and a magnetic field, means for transforming the variations of said electrostatic and said magnetic field into a single electric current variation, and means for relatively varying the components of said electrostatic and said magnetic field producing said single electric current.

In testimony whereof I affix my signature.
